(57) **CLAIM**

The ornamental design for a fuel tank, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top, front, and right side isometric view of a fuel tank embodying my new design;

FIG. 2 is a top, front, and right side isometric view thereof;

FIG. 3 is a top, front, and left side isometric view thereof;

FIG. 4 is a top, front, and left side isometric view thereof;

FIG. 5 is a top and left side isometric view thereof;

FIG. 6 is a top, rear, and left side isometric view thereof;

FIG. 7 is a top, rear, and left side isometric view thereof;

FIG. 8 is a top, rear, and right side isometric view thereof;

FIG. 9 is a top, rear, and right side isometric view thereof;

FIG. 10 is a top and right side isometric view thereof;

FIG. 11 is a bottom, rear, and right side isometric view thereof;

FIG. 12 is a bottom, rear, and right side isometric view thereof;

FIG. 13 is a bottom, rear, and left side isometric view thereof;

FIG. 14 is a bottom, rear, and left side isometric view thereof;

FIG. 15 is a bottom and left side isometric view thereof;

FIG. 16 is a bottom, front, and left side isometric view thereof;

FIG. 17 is a bottom, front, and left side isometric view thereof;

FIG. 18 is a bottom, front, and right side isometric view thereof;

FIG. 19 is a bottom, front, and right side isometric view thereof;

FIG. 20 is a bottom and right side isometric view thereof;

FIG. 21 is a front elevation view thereof;

FIG. 22 is a rear elevation view thereof;

(Continued)

FIG. 23 is a left side elevation view thereof;
 FIG. 24 is a right side elevation view thereof;
 FIG. 25 is a top plan view thereof; and,
 FIG. 26 is a bottom plan view thereof.
